UNITED STATES PATENT OFFICE.

ADEN BECKETT, OF LONG ISLAND CITY, NEW YORK.

OVEN-LOADING DEVICE.

Application filed April 25, 1921. Serial No. 464,131.

To all whom it may concern:

Be it known that I, ADEN BECKETT, a citizen of the United States, residing at Long Island City, in the county of Queens 5 and State of New York, have invented a new and useful Oven-Loading Device, of which the following is a specification.

This invention relates to a loading device adapted for use in loading glass annealing 10 furnaces to insure the glassware being properly placed within the furnace.

A further object of the invention is to provide a rotatable rack to receive the glassware, there being provided novel means 15 automatically operated for sweeping the glassware from the rack at predetermined intervals.

A still further object of the invention is the provision of a device of this character 20 which will receive material from an endless conveyor and deliver the same to the rear of the oven.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawings:

Figure 1 is a vertical sectional view 35 through the loading device and its operating mechanism, the oven in which the same is supported being shown in elevation.

Figure 2 is a plan view of the main or operating gear.

Figure 3 is a sectional view taken on line 3—3 of Figure 1; and

Figure 4 is a sectional view taken on line 4—4 of Figure 1.

Referring to the drawings in detail, the 45 reference character 5 designates the upper portion of a glass annealing furnace, the oven floor thereof being indicated by the reference character 6 and shown as supported by the brackets 7 which are secured 50 to the inner walls of the oven in any well known manner.

The loading device forming the subject matter of the present invention includes a vertical shaft 8 that extends through the 55 hollow shaft 9, which in turn operates within the hollow shaft 10, the shafts being

shown as extending through a suitable opening in the upper portion of the oven, the lower ends thereof terminating at points directly above the oven floor 6, for purposes 60 to be hereinafter more fully described.

Secured to the shaft 8 and disposed adjacent to the lower end thereof, are the arms 11, which arms have connection with the circular shelf 12 as by means of the securing 65 bolts 13, which pass through suitable openings in the arms 11 and shelf 12. The shaft 8 has its upper end disposed in a plane above the parallel supports 14 that are mounted above the oven, and has connection with the 70 relatively large gear wheel 15, which is provided with peripheral teeth 16 that mesh with the teeth of the gear wheel 17. The gear wheel 17 is mounted at the upper end of the shaft 18 and carries a beveled pinion 75 19 at the lower end thereof, the beveled pinion 19 being in mesh with the beveled pinion 20 which is keyed or otherwise secured to the horizontal power shaft 21 which in turn has connection with a suitable power 80 device not shown.

A gear wheel 22 is keyed to the hollow shaft 9 at a point adjacent to its upper end to impart rotary movement to the arm 23 which has connection with the lower end of 85 the tubular shaft 9. Formed in the upper surface of the arm 23 is a groove 24 which has inclined walls cooperating with the inclined walls on the sliding bar 25 to guide the sliding bar 25 in its movements longitudinally of the arm 23. The bar 25 has a depending right angled portion 26 which has its lower extremity disposed in spaced relation with the circular shelf 12 so that the arm 90 may be free to move thereover.

Mounted on the supports 14 are the bracket members 27 in which are supported the shafts 28 and 29 respectively, the shaft 29 supporting the pinion 30 which is in mesh with the pinion 31 carried at the lower end of 100 the shaft 28, the upper end of the shaft 28 supporting the pinion 32 which is in mesh with the gear wheel 15. The pinion 30 is in mesh with the gear wheel 22 so that rotary movement of the gear wheel 15 imparts a 105 rotary movement to the pinion 32, which in turn transmits rotary movement to the pinion 30 through the pinion 31.

At the upper end of the hollow shaft 10 is a disk 33 which carries rollers 34 that provide bearings for the gear wheel 22 to permit 110 the same to revolve freely, thereover, the

lower end of the hollow shaft 10 providing a support for the eccentric 35 which has a groove 36 formed in the lower surface thereof, the groove following the contour of the eccentric 35. Formed integral with the bar 25 is an upwardly extending shaft supporting a roller 37 which is disposed within the groove 36 so that when the arm 23 is rotated, the roller moving within the groove 36 will cause 10 a reciprocation of the bar 25 longitudinally of the arm 23, with the result that the right angled extremity 26 of the bar 25 is moved across the rack 12 to clear the same of material positioned thereon.

15 Due to the construction and arrangement of the pinions 30, 31 and 32, it will be seen that as the pinion 32 is rotated in one direction, which causes the rack 12 to be moved in one direction, the arm 23, is moved in the 20 opposite direction so that articles positioned on the rack 12 will be raked therefrom, at a predetermined interval, whereupon the right angled portion 26 will be moved to its normal position in a manner to avoid striking the 25 remaining articles on the rack.

It might be further stated that a loading device of this character may be positioned adjacent to the forward portion of an oven, and in proximity to receive material from an 30 endless conveyor.

Having thus described the invention, what is claimed as new is:—

1. In an oven, a loading device including a rotatable shelf disposed within the oven, an arm rotatable above the shelf, said arm having a groove, a bar positioned in the groove, an eccentric disposed above the bar and having connection therewith, means for rotating the arm to cause the bar to move within the groove and force material from the shelf, and means for operating the arm and shelf in opposite directions.

2. In an oven, a loading device including a rotatable shelf, an arm carrying a reciprocating bar disposed above the shelf, a roller carried by the bar, a stationary eccentric disposed above the bar and having a groove adapted to accommodate the roller, means for rotating the arm to cause the bar to reciprocate, and means for rotating the shelf in a direction opposite to the direction of rotation of the arm.

In testimony that I claim the foregoing as my own, I have hereto affixed my signature in the presence of two witnesses.

ADEN BECKETT.

Witnesses:

ALBERT PIKE,
HOWARD W. MILLER.
